(*) Notice: This patent is subject to a terminal disclaimer.

(57) **CLAIM**

(**) Term: **14 Years**

The ornamental design for a storage system, as shown and described.

(21) Appl. No.: **29/279,182**

DESCRIPTION

(22) Filed: **Apr. 23, 2007**

FIG. 1 is a perspective view of a storage system showing our new design;

Related U.S. Application Data

FIG. 2 is a side elevational view thereof;

(63) Continuation-in-part of application No. 29/268,716, filed on Nov. 9, 2006, now Pat. No. Des. 551,483.

FIG. 3 is a top plan view thereof;

(51) **LOC (8) CL.** **06-04**

FIG. 4 is a front elevational view thereof;

(52) **U.S. CL.** **D6/566**

FIG. 5 is a rear elevational view thereof;

(58) **Field of Classification Search** D6/566,

FIG. 6 is a bottom plan view thereof;

D6/567, 553; D19/65, 75, 78, 86, 90-91,

FIG. 7 is a perspective view of a second embodiment which shows a four-bin storage system;

D19/99-100; 211/10, 11, 13.1, 45, 50, 52,

FIG. 8 is a front elevational view thereof;

211/55, 87.01, 90.03, 119.005, 126.9, 126.11

FIG. 9 is a side elevational view thereof;

See application file for complete search history.

FIG. 10 is a rear elevational view thereof;

(56) **References Cited**

FIG. 11 is a top plan view thereof;

U.S. PATENT DOCUMENTS

FIG. 12 is a bottom plan view thereof; and,

1,386,878 A 8/1921 Lamp

FIG. 13 is a perspective view of a third embodiment of a storage system. The jagged broken lines form no part of the claimed design and the subject matter between the jagged lines is broken away to disclose indeterminate length and the storage system may include two or more bins.

1,738,821 A 12/1929 Gibson

The dotted-line disclosure of elements in the views is for illustrative purposes only and forms no part of the claimed design.
